CUTTER AND METHOD OF FORMING THE SAME

Emmons A. Goddard, Birmingham, Mich., assignor to Goddard & Goddard Company, Detroit, Mich., a corporation of Michigan

Application April 4, 1947, Serial No. 739,268

3 Claims.

(Cl. 76—101)

1

This invention relates generally to cutters and refers more particularly to metal disc type cutters having hub portions.

Although it will be apparent as this description proceeds that the invention is not limited to any specific type of cutter, nevertheless, it finds particular utility when employed in the manufacture of circular disc type cutters, such for example, as circular saws having hub portions at the center and having radially outwardly extending relatively thin web portions.

Circular cutters of the above general type have been difficult to economically manufacture to the close tolerances required for many uses of such cutters. Much of the difficulty heretofore encountered in producing circular cutters is due to the non-uniform rate of cooling of the cutters subsequent to the heat treating and/or side grinding operations. This uneven rate of cooling is caused by the differences in mass of the hub and web portions of the cutter. The mass of the hub portion ordinarily exceeds the mass of the web portion, and as a consequence, cools at a rate which is slow in comparison to the rate of cooling of the web portion. This differential sets up strains in the cutter which are frequently sufficiently severe to cause distortion of the cutter beyond repair.

In order to overcome the above difficulties, complicated and expensive heat treating techniques have been proposed. One heat treating process advocated is to provide some means for accelerating the rate of cooling of the hub to such an extent that this rate approximates the rate of cooling of the relatively thin web. Another process is to attempt to hold the cutter against warping or distorting by maintaining the cutter clamped between heavy plates during the heating and cooling cycles of the heat treating operation. Still another process is to leave sufficient stock on the cutter so that any buckle or distortion created during heat treating may be subsequently removed by grinding before the thickness of the cutter becomes undersize.

Even where unusual care is taken in the performance of the above heat treating processes, the results obtained are unsatisfactory. Moreover, such special heat treating processes are not conducive to producing cutters on a high production basis, and at best add materially to the cost of finished cutters.

With the above in view, it is an object of this invention to overcome the above difficulties experienced in producing heat treated circular cutters of the type stated without resorting to complicated and special heat treating processes.

2

A more detailed object of this invention is to provide a circular cutter of the general type stated wherein the mass of the hub portion approximates the mass of the radially extending web portion so that, practically speaking, the rate of cooling of the hub and rim portions are the same or nearly so. Thus the cutter may be heat treated by the simplest processes without buckling, warping or otherwise distorting the cutter. Moreover, less heat is generated in the subsequent side grinding operation, and the tendency of the cutter to distort during grinding is reduced to a minimum. It follows, therefore, that close tolerances may be held on dimensions of thickness, flatness and concavity which are prerequisites of satisfactory cutters.

The foregoing as well as other objects will be made more apparent as this description proceeds, especially when considered in connection with the accompanying drawing, wherein:

Figure 1 is a side elevational view of a circular disc type cutter constructed in accordance with this invention;

Figure 2 is a sectional view taken on the line 2—2 of Figure 1;

Figure 3 is a side elevational view of a modified form of cutter; and

Figure 4 is a sectional view taken on the line 4—4 of Figure 3.

For the purpose of illustrating this invention, a circular disc type saw is selected, although it will be understood as this description proceeds that the invention may be successfully employed in the production of various other types of cutters. Referring first to the embodiment of the invention shown in Figures 1 and 2 of the drawing, it will be noted that the reference numeral 10 designates a cutter in the form of a circular disc type saw formed of metal, such for example, as high speed steel or any other type of steel possessing the required characteristics.

In detail the saw 10 comprises a hub 11 and a web 12 extending radially outwardly from the hub. The hub is formed with a central opening 13 therethrough having a key receiving recess 14 and the periphery of the web 12 is formed with a circumferential series of cutting teeth 15. In accordance with conventional practice, the cutter is heat treated, and any orthodox process may be resorted to for this purpose. In general the cutter is heated to a temperature recommended for the particular metal employed to obtain the desired temper and is then cooled in any suitable manner.

The web 12 is relatively thin in comparison to the thickness of the hub 11 and sufficient metal

is removed from the hub to reduce the mass of the hub to a value approximating the mass of the web. In other words the bulk or quantity of material forming the hub 11 is substantially the same as the bulk or quantity of material forming the web 12, although the thickness of the hub 11 is greater than the thickness of the web. In the present instance a pair of annular recesses or grooves 16 is formed in one face of the hub in concentric relation to the axis of the cutter and a second pair of annular grooves 17 is formed in the opposite face of the hub axially opposite the grooves 16. Also, if desired, an annular recess or groove 18 may be formed between opposite faces of the cutter in the surface of the cutter surrounding the central opening 13. The amount of metal removed from the hub 11 by the above mentioned grooves, or in other words, the size and/or number of grooves is predetermined to provide the hub with a mass approximating the mass of the web 12. Thus during the cooling phase of the heat treating process, the hub 11 cools at substantially the same rate as the web 12, and the tendency for the cutter to buckle, distort or otherwise deform is reduced to a minimum. It will also be noted that the side walls of the grooves provide heat radiating surfaces which facilitate cooling of the hub 11 and assist in preventing distortion of the cutter during finish grinding the latter.

The embodiment of the invention shown in Figures 3 and 4 of the drawing features a disc type cutter 20 identical to the cutter 10 except that the recesses are in the form of a multiplicity of openings 21 drilled in the hub. The openings are spaced equal distances from each other around the axis of the hub and serve to reduce the mass of the hub sufficiently to enable the hub to cool at practically the same rate as the web during the cooling phase of the heat treating operation.

It follows from the above that both embodiments of the invention provide a disc type cutter having a hub and a web characterized in that the mass of the hub approximates the mass of the web, so that the cutter cools practically uniformly during the cooling phase of the heat treating operation. Thus deformation of the cutter by strains set up in the cutter during the cooling phase is reduced to a minimum, and the production of a cutter to close tolerances is rendered possible without resorting to special heat treating processes.

What I claim as my invention is:

1. In a method of producing a heat treated metal cutter having contiguous hub and web

portions, the web portion extending radially outwardly from the hub portion and being relatively thin as compared to the thickness of the hub portion, the steps of reducing the mass and increasing the surface area of the hub portion to an extent such that both said portions cool at the same rate from an elevated temperature, the mass of the hub portion being reduced and the surface area thereof being increased without changing the overall thickness of the hub portion, and thereafter subjecting the cutter to a heat treating process including a heating and cooling phase.

2. The method defined in claim 1, in which the mass of the hub is reduced and the surface area thereof is increased by forming openings in said hub portion at points spaced equal distances from each other around the axis of the hub portion.

3. The method defined in claim 1, in which the mass of the hub is reduced and the surface area thereof is increased by forming concentric annular grooves in at least one radial face of the hub portion.
